UNITED STATES PATENT OFFICE.

LOUIS W. GREVE, OF CLEVELAND, OHIO, ASSIGNOR OF ONE-HALF TO THE CLEVELAND PNEUMATIC TOOL COMPANY, OF CLEVELAND, OHIO, A CORPORATION OF OHIO, AND ONE-HALF TO THE CLEVELAND ROCK DRILL COMPANY, OF CLEVELAND, OHIO, A CORPORATION OF OHIO.

FLUID-OPERATED TOOL.

1,186,981.

Specification of Letters Patent. Patented June 13, 1916.

Application filed November 14, 1914. Serial No. 872,063.

To all whom it may concern:

Be it known that I, LOUIS W. GREVE, a citizen of the United States, residing at Cleveland, in the county of Cuyahoga and 5 State of Ohio, have invented certain new and useful Improvements in Fluid-Operated Tools, of which the following is a specification.

The invention relates to fluid operated 10 tools and as particularly illustrated, to rock drills. The invention has for its primary objects; the provision of an improved shell valve mechanism of simple and inexpensive construction; the provision of an improved 15 system of fluid distribution resulting in an increased efficiency of the tool and such other objects as may hereinafter appear. One embodiment of the invention is illustrated in the accompanying drawing, 20 wherein—

Figure 1 is a longitudinal section through the tool, Fig. 2 is an enlarged longitudinal section through the portion of the tool containing the fluid distribution mechanism dis- 25 closing the valve and piston in one operative position similar to that shown in Fig. 1, and Fig. 3 is a longitudinal section of that part of the tool shown in Fig. 2, with the valve and piston shown in another operative po- 30 sition.

Referring to the general arrangement of parts as disclosed in Fig. 1, 1 is the valve casing which carries the various fluid distribution valves, 2 is the piston cylinder casing which is securely attached to the valve casing and in which the piston 3 recipro- 35 cates, 4 is a tappet carried by the tappet guide block 5 secured to the casing 2, the tappet 4 being adapted to be intermit- 40 tently engaged by the piston 3, 6 is the drill shank, the drill being shown as broken off, and is carried by and guided by the chuck 7, 8 is a sleeve or shell valve adapted to recipro- 45 cate longitudinally within the valve block 9, 10 is a valve block button adjoining the valve block and which is held in place by the casing 2, 11 is the controlling valve, manually operated and carried by the bush- 50 ing 12 secured within the valve casing 1, 13 is a feed rod piston cylinder secured to the rear of the casing 1 and which carries therein a piston 14 adapted to be forced rearwardly by fluid pressure supplied to the

chamber 15, 16 is a feed rod adapted to be actuated by the piston 14 and is for the purpose of feeding the tool to the work, the feed rod being adapted to engage some sort of support opposite the surface to be drilled, and 17 is a closed hollow handle for the tool adapted to carry a supply of lubricant.

The piston 3 is controlled by the sleeve valve 8 which is in turn controlled by the piston 3. Referring more particularly to Figs. 2 and 3 the fluid distribution system consists of the manual control valve 11 through which fluid is fed to the tool from a suitable source, entering the tool through the passage 18 and thence into the storage reservoir 19 through the passage 20. The purpose of the reservoir 19 is for storing a quantity of air under pressure at a point adjacent the sleeve valve 8 so that a constant and immediate supply of fluid under pressure is available the instant the controlling valve is operated. The reservoir 75 also insures a uniform pressure of fluid at all times during the operation of the tool.

The fluid passes from the reservoir 19 through the passage 21, which is of greater capacity than the passage 20, into an annular recess 22 in the rear end of the valve casing 1, and it is from this recess that all fluid for operating the tool is supplied. When the sleeve valve 8 and the piston 3 are in the position shown in Figs. 1 and 2 the circulation of fluid is as follows: Fluid enters the passage 23 in the lower part of the rear end of the valve block 9 from the annular recess 25 cut in the periphery of the sleeve valve 8, through the port 26 in the valve block 9 into the passage 27 and thence through the port 28 into the front end of the piston chamber 29 where it acts upon the front end of the piston 3, thereby driving the piston rearward.

The fluid in the piston chamber 29 in the rear of the piston 3 is exhausting through the port 30 leading to the passage 31, and through the port 32 leading from the chamber 29 to the passage 31. The passage 31 communicates with an exhaust port 33 which leads from the annular recess 34 cut in the valve block 9 to the annular exhaust passage 35 surrounding the valve block and opening to the atmosphere through the exhaust passage 36 at the bottom of the valve

casing 1. Fluid, therefore, exhausts from the passage 31 through port 33, annular exhaust passage 35, and to the atmosphere through the passage 36.

5 The sleeve valve 8 is held in the position shown in Figs. 1 and 2 by means of a constant supply of fluid under pressure supplied to the annular recess 34 through the port 37 which communicates with the passage 38 which is constantly open to the annular recess 22 in the valve casing 1. Fluid in the annular recess 34 acts upon the forward annular pressure face or area 39 on the outside of the sleeve valve 8, overrunning by reason of greater area the pressure exerted upon the rearward annular pressure area 40 supplied with fluid through the port 24 and passage 23. The rearward pressure area 41 constantly receives a supply of fluid 10 under pressure from the reservoir 19 through passage 21, annular groove 22, port 42 and port 43. In the rear portion of the valve 8 as shown in Figs. 1 and 2, the pressure on the rearward pressure area 41 is reduced below the pressure on the pressure area 39 because of the passage 44 in the sleeve valve 8 which leads from the pressure area 41 to the forward end of the sleeve valve and opens into the rear of the piston chamber 29 through the port 45. As the fluid in the piston chamber 29 is exhausting behind the piston 3, the pressure on the surface 41 is considerably lower than the pressure on the pressure area 39 by reason of the low pressure in the passage 44 which is bleeding the fluid from the pressure area 41. The extreme rear end area 46 of the sleeve valve is not receiving any pressure above exhaust pressure while the valve is in the rearward position, and as the pressure area 41 is of smaller area than the pressure area 39 and receives less pressure, and as the area of the pressure area 40 is less than the pressure area 39, the valve will remain in the rearward position until pressure conditions on the various pressure areas are changed.

When the piston 3 moves rearward it first closes the exhaust port 30, and when the rear end enters the sleeve valve the exhaust port 32 is shut off from the piston chamber, and the extreme forward pressure area 47 of the sleeve valve 8 is thence subject only to exhaust pressure. Further rearward movement of the piston covers the port 45 which port establishes communication between the piston chamber and the rearward pressure area 41, and as the fluid through the port 45 can no longer exhaust the pressure on the pressure area 41 immediately rises to that on the pressure area 39, and together with the constant pressure on the rearward pressure area 40 and the pressure on the extreme rear area 46 overcomes the constant pressure on the pressure area 39

resulting in the shifting of the valve to the forward position as shown in Fig. 3. When the front end of the piston 3 passes the port 30' the pressure in the front end of the piston chamber is suddenly reduced and aided by the compression of the trapped fluid in the rear end of the chamber the piston is cushioned and stopped before it engages the rear end of the chamber.

Referring to Fig. 3 the circuit of the fluid from the reservoir 19 when the parts are in the position shown therein is as follows. The fluid enters the annular recess 22 through the passage 21, thence into the passage 23 and through the port 43 into the extreme rear end of the piston chamber forcing the piston 3 forward. The fluid in front of the piston 3 exhausts to the atmosphere through the port 28, passage 27, exhaust port 49, annular recess 34, exhaust port 33 at the top of the valve block 9, annular exhaust passage 35 surrounding the valve block and through the exhaust passage 36. Fluid also exhausts at the first part of the forward stroke of the piston 3, through the port 30', passage 31, port 33, annular passage 35 and exhaust passage 36.

The sleeve valve 8 remains in the forward position until the port 38' communicating with the piston chamber 29 and the constant fluid supply passage 38, is closed by the forward end of the piston 3 covering the port 38'. After the sleeve valve 8 had been shifted forwardly the pressure in the passage 38 was reduced owing to the exhausting of the fluid in the forward end of the piston chamber, therefore reducing the pressure on the forward pressure area 39 which is supplied with fluid through the port 37 leading from the passage 38. This reduction of pressure as well as the reduction of pressure on the extreme forward pressure area 47 on the sleeve valve when the piston 3 entered the sleeve valve on its rearward stroke, caused the forward shifting of the sleeve valve into position shown in Fig. 3, therefore when the front end of the piston 3 covers the port 38' upon its forward stroke and the rear end of the piston moves out of the sleeve valve subjecting the pressure area 47 to the high pressure in the rear of the piston 3, the pressures thus exerted upon the pressure areas 39 and 47, because of their superior area will overcome the pressure exerted upon the rearward pressure areas 41 and 46 and the valve will be forced rearwardly. The pressure on the rearward pressure area 40 is reduced because the fluid is exhausting through the exhaust port 33 and therefore offers but little resistance to the rearward movement of the valve.

Briefly, the sleeve valve is shifted forwardly by high pressure exerted on the rearward pressure areas 41 and 40 overcoming the high pressure on the forward pressure

area 39 and the low pressure on the extreme forward pressure area 47. The rearward movement of the valve is caused by high pressure on the extreme forward pressure area 47 and the forward pressure area 39 overcoming low pressure on the rearward pressure area 40 and high pressure on the rearward pressure areas 41 and 46.

A constant supply of fluid is supplied to the pressure area 39 tending to move the valve rearwardly and a constant supply of fluid is supplied to the rearward pressure area 41 tending to move the valve forward, the movement of the valve being controlled by the piston which opens and closes various ports and passages for reducing and increasing pressure on other pressure surfaces serving to alter the balance of pressure first on one end of the valve and then on the other. The valve 8 controls the admission and exhaust to the piston chamber in such manner as to cause the piston 3 to reciprocate within the piston chamber.

The sleeve and piston valve are lubricated by means of a supply of oil inclosed within the handle 17, the oil being conducted to the valve through the port 50 leading from the handle to the controlling valve 11, thence around the groove 51 in the periphery of the valve 11 through the port 52 into the annular recess 22 from whence it is carried to the moving parts.

The operation of the tool is as follows. The tool is first adjusted to the work ready for drilling and the valve 11 turned so that fluid may pass from the passage 18 in the valve through the passage 20 into the storage reservoir 19. Starting with the parts in the position shown in Fig. 2, the fluid passes through the passage 21 into the annular groove 22 and thence into the passage 23, through port 24 around the annular groove 25 in the valve 11, through the port 26, and passage 27 into the front end of the piston chamber 29 through the port 28. The piston 3 is forced rearward by the fluid thus entering the chamber, and the fluid in the rear end of the piston chamber is exhausting through the ports 30 and 32 into the exhaust passage 31 and thence through the port 33, the annular passage 35 and finally through the exhaust passage 36 to the atmosphere. When the piston 3 covers the small port 45 in the interior of the valve 8, the increased pressure caused thereby on the pressure area 41 causes the valve to move forward to the position shown in Fig. 3. The forward shifting of the valve closes the port 24 and opens the port 43 leading to the rear end of the piston chamber, thereby permitting the entrance of the fluid to the rear end of the piston chamber which forces the piston 3 forward to strike the tappet 4 a sharp blow which in turn imparts the blow to the drill tool 6. The forward shifting of the valve opens the

port 49 leading from the passage 27, which allows the fluid in the front end of the piston chamber to exhaust through the port 28, passage 27, port 49, around annular recess 34, exhaust port 33, annular passage 35 and 70 exhaust passage 36.

When the piston 3 moves forward sufficient distance to cover the port 38', the increase of pressure in the passage 38 communicating with the pressure area 39 by means 75 of the port 37, together with the piston chamber pressure exerted upon the pressure area 47, causes the valve to be shifted rearwardly to the starting position as shown in Figs. 1 and 2. The rearward shifting of the 80 valve again causes the piston to move rearward and the cycle of movements is continued as long as fluid is supplied to the reservoir 19.

The rapid and intermittent impact of the 85 piston 3 upon the tappet causes the drill to gradually bore a hole in the rock or other substance to be drilled.

It is obvious that certain modifications may be made in the arrangement of the valve 90 piston and ports without departing from the spirit of the invention.

What I claim is:

1. In combination in a fluid operated tool having a piston adapted to reciprocate 95 within a cylinder, a sleeve valve for controlling the piston into which the piston is moved, provided with a pressure surface, means for supplying a constant supply of fluid to such surface to hold the valve in one 100 operative position, an oppositely disposed pressure surface on the valve having greater area than the first pressure area, means for supplying a constant supply of pressure to the oppositely disposed surface, an exhaust 105 passage communicating with the interior of the cylinder and a port in the valve establishing communication between the oppositely disposed surface and the interior of the cylinder adapted to be closed by the piston when the piston enters the valve.

2. In combination in a fluid operated tool, having a piston adapted to reciprocate within a cylinder, a sleeve distributing valve for controlling the piston, a fluid supply inlet 115 controlled by the valve, a passage connecting the inlet with the interior of the cylinder for supplying fluid to one end of the cylinder, an outlet port in the passage between the inlet of the cylinder, an exhaust 120 port controlled by the valve for exhausting fluid from the same end of the cylinder and an annular groove surrounding the valve for establishing communication between the said ports when they are uncovered by the 125 sleeve valve.

3. In combination in a fluid operated tool having a piston adapted to reciprocate within a cylinder, a distributing valve for controlling the fluid for operating the piston, 130

- a fluid supply inlet, a fluid supply passage connecting the inlet with the interior of the cylinder, an outlet port in the fluid supply passage intermediate the supply inlet and the cylinder controlled by the valve, an exhaust port controlled by the valve substantially in the same plane with the outlet port and adapted to be closed by the distributing valve, and an annular groove 5 and the cylinder controlled by the valve, an exhaust port controlled by the valve substantially in the same plane with the outlet port and adapted to be closed by the distributing valve, and an annular groove 10 rounding the valve for connecting the said ports when the valve is moved to open the ports.
4. In combination in a fluid operated tool having a piston adapted to reciprocate with 15 in a cylinder, a distributing valve for controlling the fluid for operating the piston, a fluid supply inlet, a fluid supply passage connecting the inlet with the interior of one end of the cylinder, an outlet port in the 20 fluid supply passage intermediate the supply inlet and the cylinder controlled by the valve, an exhaust port controlled by the valve substantially in the same plane with the outlet port for exhausting fluid from the 25 same end of the cylinder and adapted to be closed by the distributing valve, and an annular groove surrounding the valve for connecting the said ports when the valve is moved to open the ports.
5. In combination in a fluid operated tool having a piston adapted to reciprocate with 30 in a cylinder, a sleeve valve for controlling the piston provided with oppositely disposed differential pressure areas, and adapted to receive the piston, means for constantly supplying fluid pressure to the said pressure areas, an exhaust passage communicating with the cylinder, and a port in the valve establishing communication between 35 the pressure area of greater area and the interior of the cylinder adapted to be closed by the piston to prevent the escape of fluid from the pressure area of greater area into the cylinder when the port is closed.
6. In combination in a fluid operated 40

tool having a piston adapted to reciprocate within the cylinder, a fluid chamber, a distributing valve for controlling the movement of the piston adapted to reciprocate within a valve chamber, an annular groove 50 in the valve chamber surrounding the distributing valve, an annular enlargement upon the valve adapted to operate in the groove, a fluid supply passage leading from the fluid supply to the piston cylinder and 55 communicating with the annular groove through a port adapted to be closed by the annular enlargement of the valve when the valve is in one operative position, an exhaust passage leading from the annular 60 groove adapted to be closed by the annular enlargement of the valve when the valve is in position to close the said port, and means on the valve for closing the supply passage between the fluid supply and the piston cylinder when the valve is moved to uncover the said port and the said exhaust passage to establish communication therebetween.

7. In combination in a fluid operated tool, a casing, a piston chamber provided 70 with admission ports leading through its side walls, a shell valve at the end of the chamber through which fluid from the admission ports passes to the chamber, a piston working through the chamber and 75 through the shell valve, a feed cylinder and piston in alignment with the piston chamber but spaced away therefrom, and a storage reservoir located in the space between the ends of the piston chamber and feed 80 cylinder, such reservoir being supplied with fluid under pressure and communicating with the said ports.

In testimony whereof I have hereunto signed my name in the presence of the two 85 subscribed witnesses.

LOUIS W. GREVE.
